Primary Examiner — Susan E Krakower*Assistant Examiner* — Lisa A Grabenstetter(74) Attorney, Agent, or Firm — Patent Law Agency, LLC; Peter Ganjian(57) CLAIM

The ornamental design for a skull purse, as shown and described.

DESCRIPTION

FIG. 1 is a right side perspective view of a skull purse showing my new design, shown with unclaimed environment;

FIG. 2 is a front, right side perspective view thereof;

FIG. 3 is a back, right side perspective view thereof;

FIG. 4 is a second right side perspective view thereof;

FIG. 5 is a left side perspective view thereof;

FIG. 6 is a top perspective view thereof;

FIG. 7 is a bottom perspective view thereof;

FIG. 8 is a front perspective view thereof, shown in an open condition; and,

FIG. 9 is a top perspective view thereof, shown in an open condition.

The broken lines depicting a zipper and interior of the purse represent unclaimed portions of the design.

The broken line showing a human figure, in FIG. 1, represents unclaimed environment.

1 Claim, 9 Drawing Sheets(56)
